CURTAIN CLIP RING

Nolan K. Rhoades, Beloit, Wis., assignor to Western Newell Mfg. Co., Freeport, Ill., a corporation of Illinois

Filed Mar. 7, 1960, Ser. No. 59,641

Term of patent 14 years

(Cl. D21—1)

FIG. 1 is a side view, substantially twice full size, of a curtain clip ring embodying the design of my invention; FIG. 2 is an end view as seen from the right of FIG. 1; FIGS. 3 and 4 are a bottom view and top view of FIG. 1, respectively, and FIGS. 5 and 6 are sectional details taken on the lines 5—5 and 6—6 of FIG. 1, respectively.

I claim:

The ornamental design for a curtain clip ring, as shown.
